GUN

Jessie T. Ivy, Seattle, Wash.

Application October 24, 1955, Serial No. 38,534

Term of patent 14 years

(Cl. D30—1)

Fig. 1 is an elevation of a gun, as seen from the left hand side, embodying my new design.

Fig. 2 is an elevation of the same as seen from the right hand side.

Fig. 3 is an underside view of the same.

Fig. 4 is a view of the gun as seen from the forward end.

The characteristic features of the design reside in the solid line portions.

I claim:

The ornamental design for a gun, as shown and described.
